CLAIM

The ornamental design for an all-terrain vehicle and/or replica, as shown and described.

DESCRIPTION

FIG. 1 is a front left perspective view of an all-terrain vehicle and/or replica showing our new design;

FIG. 2 is a front right perspective view of the design shown in FIG. 1;

FIG. 3 is a rear right perspective view of the design shown in FIG. 1;

FIG. 4 is a rear left perspective view of the design shown in FIG. 1;

FIG. 5 is a right side view of the design shown in FIG. 1;

FIG. 6 is a left side view of the design shown in FIG. 1; and,

FIG. 7 is a top view of the design shown in FIG. 1. The bottom of the all-terrain vehicle and/or replica forms no part of the claimed design. The broken lines shown in the figures are included for the purpose of illustrating portions of the all-terrain vehicle and/or replica and form no part of the claimed design.
